UNITED STATES PATENT OFFICE.

SAMUEL P. JOHNSON, OF LONGACRE, WEST VIRGINIA.

AUTOMATIC MECHANISM FOR STOPPING TRAINS.

1,345,599.

Specification of Letters Patent.

Patented July 6, 1920.

Application filed June 28, 1919. Serial No. 307,347.

To all whom it may concern:

Be it known that I, SAMUEL P. JOHNSON, a citizen of the United States, residing at Longacre, in the county of Fayette and 5 State of West Virginia, have invented new and useful Improvements in Automatic Mechanism for Stopping Trains, of which the following is a specification.

This invention relates to means for automatically stopping railway trains when a block signal is set against the train, and the object of the invention is to provide simple and improved means for automatically applying the air brakes and closing 10 the throttle by means carried by a locomotive and actuated by an electric circuit which is under the control of the usual semaphore of any ordinary block signal system. 15 With these and other objects in view, the present invention consists in the combination and arrangement of parts as will be hereinafter more fully described, illustrated in the accompanying drawings and 20 particularly pointed out in the appended claims, it of course being understood that changes in the form, proportion, size and minor details may be made, within the scope 25 of the claims, without departing from the spirit or sacrificing any of the advantages 30 of the invention.

In the drawings,

Figure 1 is a side elevation showing an embodiment of the present invention, the 35 bottom portion of a semaphore pole being broken away to show the switch which is controlled by the semaphore, and the outline of a locomotive being shown in dotted lines.

Fig. 2 is a vertical sectional view, on an enlarged scale, taken through the cylinder mechanism for actuating the throttle lever.

Fig. 3 is a fragmentary plan view showing the connection between the throttle lever 45 and the piston of the cylinder.

Fig. 4 is a detail cross sectional view on the line 4—4 of Fig. 2.

Fig. 5 is a detail perspective view of the yoke or seat for the support of the throttle 50 lever cylinder.

Fig. 6 is a rear view of the contact member carried by the locomotive.

Fig. 7 is a side elevation of Fig. 6.

Fig. 8 is a detail perspective view of the

contact rail which is placed upon the rail- 55 road track between the rails thereof.

In the accompanying drawings, 1 designates an ordinary railway track on which has been shown in dotted lines the outline of a locomotive 2 which has the usual train 60 pipe 3 of any ordinary air brake system.

In carrying out the present invention, a branch pipe 4 is provided, said pipe leading from a forward portion of the train pipe 3 as indicated at 5 and extending rearwardly 65 and connected to a cylinder 6, preferably by means of a flexible hose or pipe section 7, the upper end of which is connected to the rear portion of the cylinder 6. This cylinder is provided with a piston 8 having a piston rod 9 working through a stuffing box 10 provided upon the rear end of the cylinder. The forward end portion of the cylinder is provided with a plurality of openings 11 for the escape of air when the piston 8 is moving forwardly. 70

The cylinder 6 is mounted in a seat which includes a substantially U-shaped yoke 12 having an arm or shank 13 extending at substantially right angles to the plane of the yoke and lying upon a suitable bracket 14 secured to the side of the locomotive boiler in front of and adjacent the cab of the locomotive. Each member of the yoke is provided with a set screw 15 which takes 85 into a socket in the adjacent side of the cylinder so that the latter may rock or oscillate vertically upon the axis afforded by the set screws. The shank or arm 13 is provided at its outer end with an opening 17 for the reception of a fastening 18 which extends through the bracket 14 and pivotally connects the arm to the bracket. An arcuate slot 19 is provided in the arm 13 and arranged with the opening 17 as the 90 center from which the arc is struck. A fastening 20 extends through the slot 19 and into the bracket 14 so as to hold the arm down against the bracket and limit the swinging movement of the arm. By the 95 mounting just described, it will be seen that the cylinder 6 may oscillate vertically about its center on the pivots 15, and may swing horizontally on the fastening 18 as a center so as to accommodate itself to conditions as 100 will be hereinafter described. Because of the movements of the cylinder 6, the flexible pipe portion 7 is employed.

105

- The connection between the piston rod 9 and the throttle lever A, as shown in Figs. 2 and 3 of the drawings includes a ring 21 internally screw threaded and fitted to the rear end of the piston rod. A pair of spaced arms 22 extend rearwardly from the ring and embrace or straddle the throttle lever. The arms 22 are provided with alined longitudinal slots 23 through which extends a pin 24 which also extends through the throttle lever. Another pin 25 extends through the outer ends of the arms 22 and normally lies against the outer side of the handle 26 pivoted upon the throttle lever as at 27, and controlling the ratchet lock for the throttle. Said ratchet lock is not shown in the drawings as it forms no part of the present invention and is a common and well known device. When the piston 8 is moved forwardly, it will be seen that the initial movement presses the pin 25 against the handle 26 so as to first release the locking ratchet, the connection between the piston rod 9 and the throttle lever sliding across the latter without moving the same until the closed rear ends of the slots 23 engage the pin 24, whereupon the throttle lever is pulled forwardly and the throttle is thereby closed.
- At a suitable place on the branch pipe 4, preferably near the forward end thereof there is a valve 27 which is normally closed and designed to be opened so as to admit pressure from the train pipe 3 to the cylinder 6 so as to close the throttle. This valve is provided with a crank arm 28 pivotally connected to a link 29 which is in turn pivotally connected to a lever 30 fulcrumed intermediate of its end as at 31 upon a suitable bracket 32 secured to a convenient part of the locomotive. A solenoid 33 is suitably mounted upon the locomotive, say at the underside of the running board 34 of the locomotive, and the core of the solenoid is connected to the lever 30 by a link 35. The connection between the link 35 and the lever 30 is preferably a pivoted and slidable connection in order that the link 35 may travel as nearly as possible in a straight line so as to avoid binding of the core in the solenoid.
- When the solenoid is energized, the link 35 will be moved endwise resulting in the opening of the valve 27, whereby the train pipe pressure will be reduced and the brakes applied. The train pipe pressure escaping through the valve 27 is conducted by the pipe 4 to the cylinder 6, and thereby the throttle lever 30 is first unlocked and then moved to close the throttle and stop the operation of the locomotive.
- Inasmuch as the piston rod 9 is pivotally connected to the throttle lever the cylinder 6 is mounted to move horizontally about the fastening 18 as a center so as to accommodate the cylinder to the arcuate swing of the connection between the piston rod 9 and the

throttle lever. Moreover the cylinder 6 is mounted to oscillate vertically upon the pivot pins 15 so as to accommodate the cylinder to any up or down movements of the throttle lever.

From the foregoing description it will be understood that the air brakes and the throttle lever are under the control of the solenoid 33, which solenoid is normally de-energized and is included in a normally open circuit which includes a conductor 35 leading from one end of the solenoid and grounded upon or connected to a suitable part of the locomotive as at 36. Another conductor 37 leads from the other end of the solenoid to a contact member carried by the locomotive in position to wipe across a stationary contact member provided upon the railway track. This contact member includes a pair of spaced arms 38 having a spacing block 39, of insulating material, interposed therebetween and secured thereto by suitable fastenings 40. A cross-head 41 is secured across the top of the contact member and said cross-head is in turn connected to some suitable part of the locomotive, say to the rear portion of the cow-catcher, as indicated in Fig. 1 of the drawings. A brush contact 42 is secured between the lower ends of the arms 38 by means of fastenings 43 which pass through slots 44 in the arms so as to provide for vertical adjustment of the brush to compensate for wear.

Between the rails of the track and at a suitable distance from each semaphore pole 45 there is a stationary contact member including a rail 46, preferably of wood secured to the ties and disposed in the path of the contact brush 42. The top of the rail 46 is provided with a plate 47 of conductive material, and from this plate or shoe leads a conductor 48 which extends to a stationary contact jaw 49 preferably located in the hollow base 50 of the semaphore pole 45. A knife switch member 51 co-operates with the jaw 49 and is suitably fulcrumed within the casing 50, as for instance upon a post 52. A rod 53 is connected to the blade or arm 51 and is also connected at its upper end to the movable semaphore arm 54 so that the switch member 51 will be moved to open position when the semaphore arm 54 is set for a clear track. Of course the switch arm 51 will be moved into engagement with the jaw or contact member 49 of the switch when the semaphore arm 54 is set to indicate that the block is closed. A conductor 55 leads from the contact 49 to a battery 56. A conductor 57 leads from the battery 56 to one of the rails of the track.

Under normal conditions, the solenoid circuit is open as hereinbefore described, and the semaphore circuit is also open, first because there is no connection between the con-

ductor 57 and the contact plate 47, and for the further reason that the switch arm 51 is normally out of engagement with the contact 49. When the semaphore arm 54 is set 5 to indicate a closed block, the switch 51 will be closed, but the semaphore circuit will still be open because of the lack of a connection between the plate 47 and the conductor 57. When a train approaches the block and 10 the contact brush 42 engages one end of the contact plate 47, the two circuits will be joined to form a single closed circuit, whereupon the solenoid 33 will be energized, resulting in the opening of the valve 27 and 15 the automatic application of the air brakes and the closing of the throttle, whereby the train will be brought to a complete stop in time to avoid a collision or derailment.

What I claim is:

20 1. In automatic mechanism for stopping trains, the combination with an air brake system and a throttle lever, of a cylinder mounted to oscillate upon a transverse axis disposed intermediate the ends of the cylinder and provided with a piston connected with the throttle lever, a branch pipe leading from the train pipe and having a flexible connection with the cylinder at the throttle lever end thereof a valve included in the

branch pipe, and means for opening the 30 valve to reduce the train pipe pressure and apply the brakes and also to actuate the piston and close the throttle.

2. In automatic mechanism for stopping trains, the combination with an air brake 35 system and a throttle lever, of a cylinder, a yoke embracing the cylinder, pivot pins connecting the cylinder to the yoke, a piston in the cylinder, a connection between the piston and the throttle lever, a branch pipe 40 leading from the train pipe and having a flexible connection with the cylinder, a valve included in said branch pipe, and means for opening the valve to establish communication between the train pipe and the cylinder. 45

3. In automatic mechanism for stopping trains, the combination with an air brake system and a throttle lever, of a cylinder having a piston connected to the throttle lever, a swinging yoke embracing the cylinder, pivot pins supporting the cylinder upon the yoke, a branch pipe leading from the train pipe, a flexible connection between the branch pipe and the cylinder, a valve included in the branch pipe, and means for 50 opening the valve to establish communication between the train pipe and the cylinder. 55

SAMUEL P. JOHNSON.
